UNITED STATES PATENT OFFICE

110,886

DESIGN FOR A PISTOL

Harry A. Stevens, Hartford, Conn., assignor to
Colt's Patent Fire Arms Manufacturing Company,
Hartford, Conn., a corporation of Connecticut

Application April 8, 1938, Serial No. 76,386

Term of patent 14 years

To all whom it may concern:

Be it known that I, Harry A. Stevens, a citizen of the United States, residing at Hartford, in the county of Hartford and State of Connecticut, have invented a new, original, and ornamental Design for a Pistol, of which the following is a specification, reference being had to the accompanying drawing, forming part thereof.

Of the drawing:

Fig. 1 is a side elevational view of a pistol embodying the new design, the grip portion being shown in dot and dash lines.

Fig. 2 is a top plan view of the pistol shown in Fig. 1.

Figs. 3, 4, and 5 are sectional views taken on the lines 3—3, 4—4, and 5—5, respectively, in Fig. 1.

The stippled portions in the drawing represent a dulled or non-reflecting finish.

The dominant features of the design are found in the provision of a barrel having in general a diameter greater than the thickness of the receiver, in the substantially straight line joinder of the top and bottom edges of the barrel and receiver, and in the flattening of the sides of the barrel to effect a co-planar joinder of the sides of the barrel and receiver.

I claim:

The ornamental design for a pistol, as shown and described.

HARRY A. STEVENS.
